SHINGLE ELEMENT

Donald F. Fradette, Cleveland, Ohio

Application March 12, 1936, Serial No. 68,560

2 Claims. (Cl. 108—8)

The present invention relates to a shingle element and is particularly concerned in the method of arching or bowing a shingle element of thin gauge metal stock to render its use more advantageous in the roofing industry.

As heretofore practiced it has been difficult to hold a shingle made of thin metal stock down at the butt end; other than by interlocking flanges or cementing it to or with the felt base thereunder.

This I have successfully attained by the method used in forming the shingle element as herein set forth. The manufacturing cost of production is almost insignificant, and no peculiar skill is necessary to produce the element in the proper shape because it is a contrivance of extraordinary simplicity.

The shape of the element longitudinally and transversely is such that when it is surmounted on the felt base and secured to place, the butt portion thereof is forced into intimate contact with the base and the element below, so that accumulation of water, ice and snow thereunder at critical weather periods is practically eliminated.

The inherent resiliency of the metal, and its tendency to return to its former preformed shape, contribute to the successful results herein set forth.

In making the shingle element there is given to it the desired degree of curvature to impart to it the necessary compression, so that when it is nailed to place it will be equally stressed, and will be maintained in substantial accurate and continuous engagement with the felt base and its contact surface with the element below.

The felt base used with the element is available on the market in various forms, therefore a description thereof is not given in full herein.

The possibilities of application of the invention are many for instance, the elements may be applied to side walls or the like, of various buildings.

Other objects and features of novelty will appear from the description following hereinafter and from the claims.

For better understanding of this invention, reference is made to the accompanying drawing, which illustrates convenient constructional forms of this invention by way of example only and in which:

Fig. 1 illustrates the shingle in perspective showing its formation.

Fig. 2 illustrates another form of the shingle element in perspective.

Fig. 3 illustrates in perspective, the element

surmounted on felt bases, with a cushioning felt of ribbon configuration therebetween for the nail heads; the base element and the cushioning felt are shown in cross section.

Fig. 4 illustrates in perspective, the element, with bases shown in section associated therewith, the cushioning strip shown in Fig. 3 being eliminated.

Fig. 5 illustrates in perspective, the elements shown in Fig. 1 in association with base element, 10 below and above in cross-section.

Fig. 6 illustrates perspectively an explanatory view showing the relation of the cushioning strip for nail-heads with the transverse aligning flange adapted to position the cushioning strip on the 15 element.

In the drawing like characters of reference designate similar parts.

The shingle element, as a whole, of my invention is designated in Fig. 1 by the respective numbers 10, 11 and 12.

Between the portions 10 and 11 there is provided a transverse bend so that the portion 11 extends slightly downwardly, giving the element longitudinally an arch. Paralleling the bend or bead 13 at the end of the portion 10 there is provided a reinforcing flange 12 integral with the portion 10 and is adapted to directly shield the edge of the felt base, and also to provide a suitable bearing and support for the end of the plate, and further tends to prevent buckling of the plate element, when the same is secured to a structure by suitable fastening means such as nails 20, 20, as shown in Fig. 6.

In Fig. 2 the plate element 14 is provided with a bead 15 having a cylindric exterior circumference 16 to give the element an arch, otherwise the construction of the element is the same as that shown in Fig. 1.

In Fig. 3 the ribbon-like cushioning strip 17 for the nail heads is shown between the base felt 18 on which the plate element 14, shown fragmentarily, is mounted.

In Fig. 4 the cushioning strip is eliminated, and the base 18 is shown stopping just behind the head 15.

In Fig. 5 the element shown in Fig. 1 is shown in assembled relation.

In Fig. 6 the elements are shown in spaced relationship and showing a plate element 14 provided with an integrally formed transverse vertically extending rib or flange 19 paralleling the bead of semicylindrical configuration formed in the plate element. This flange is provided as an aligning and limiting means so that the cushion-

ing ribbon can be symmetrically interposed between the elements in making up the roof. The nails 20, 20 are shown in position in the cushioning strip. It will be noted that the element is provided at its extremities with a transverse flange thus reinforcing the plate. The transverse bead also strengthens the plate transversely; besides it provides a means in the plate by which the plate may be given the proper arch form.

From the foregoing it should be apparent that the objects previously presented have been attained by means of the construction covered in the specification.

While I have herein shown and described a preferred arrangement, it will be readily understood that changes and modifications therein may be found desirable or essential in meeting the various exigencies of use, and I desire to be understood as reserving the right to make any and all such changes or modifications as may be found desirable or essential, in so far as the same may fall within the spirit and scope of the invention as expressed in the accompanying claims when construed in the light of the prior art.

Having thus described my invention, what I claim is:—

1. A plane metallic shingle element having a

longitudinal transverse bend therein and a transverse downwardly extending flange at an end thereof, a felt base below the element, a nail-head ribbon like cushioning strip, an aligning flange therefor, the said strip abutting the transverse bend and positioned rearwardly thereof and confined between the bend and the aligning flange, nails in the nail-head cushioning strip, the transverse bend imparting sufficient resistance to the element so that there will be simultaneously induced a counter force in the element in opposition to exterior disturbing lifting forces.

2. A metallic shingle element having two angularly related plane portions formed by a bend extending transversely thereacross, one of the portions having a surface much greater than the other surface constituting the element, a ribbon like nail head cushioning strip surmounted on the lesser surface rearwardly of and in registry with the transverse bend, a felt base of conventional structure positioned below the shingle element, nails acting through said strip and said element to force the angularly related portions of the element into substantial parallelism with each other and with the cooperating base, thereby by constraining the butt end of the element to resist exterior lifting forces.

DONALD F. FRADETTE.
